UNITED STATES PATENT OFFICE.

OTTO ERNST, OF LARCHMONT, NEW YORK.

ELECTRIC SIGNAL SYSTEM.

SPECIFICATION forming part of Letters Patent No. 760,976, dated May 24, 1904.

Application filed September 22, 1903. Serial No. 174,151. (No model.)

To all whom it may concern:

Be it known that I, OTTO ERNST, a citizen of the United States, and a resident of Larchmont, in the county of Westchester and State 5 of New York, have invented a new and Improved Electric Signal System, of which the following is a full, clear, and exact description.

My invention relates to electric signaling, 10 and more particularly to the production of a simple and reliable signal for use in connection with electric railways and adapted to warn the engineer at the power-house and the motorman whose train happens to be near 15 the seat of trouble upon a particular part of the line.

Reference is to be had to the accompanying drawings, forming a part of this specification, in which similar characters of reference indicate 20 corresponding parts in all the figures.

Figure 1 is a diagram of the wiring of my system. Fig. 2 is a vertical cross-section showing the invention as applied, and Fig. 3 is a perspective view of a part of the wiring.

25 The railway is divided into blocks or sections A B, each section being somewhat independent of the others for the reason that the signal mechanism and power-supply are entirely distinct from each other. A dynamo 1 or equivalent source of electricity is provided 30 with terminals 2 3 in the usual manner. From the terminal 2 a wire 4 is connected with distribution-wires 5 6, leading to the different blocks. Of course any number of such

35 wires may be used. In the drawings, which show the invention in one of its simplest forms, the wire 5 leads to the block A and the wire 6 leads to the block B. A conduit 7 is provided for the purpose of protecting the

40 wires which emerge from the conduit at the nearest intersection of the block in which the wires are to be connected with signals. A number of electric bells 8, preferably of the continuous-ring type, are disposed within the

45 block B, and intermediate of these bells are glow-lamps 9. Both the glow-lamps and the electric bells just mentioned are connected by wires 8^a 8^b 8^c with wires 7^a and 10. The wires 6 and 7^a are uncovered, while the wire 50 10 is preferably covered, as shown. The

covered wire 10 is connected with a wire 11, this wire being connected with a bell 12 and a glow-lamp 13, and the wire 7^a is also connected with this glow-lamp and bell. The wire 14 is for the purpose of affecting the block A 55 and is connected with an insulated wire 15 and a number of bells 16 and glow-lamps 17, which constitute bridges from the wire 14 to the wire 15. Similarly a bell 18 and a glow-lamp 19 bridge these two wires 14 and 15. 60

The dynamo 1, the lamps 13 and 19, and the bells 12 and 18 are all disposed at the power-station. By means of a circuit-band 20, having substantially the form of a hook and provided with an insulating-handle 20^a, 65 the wires 6 7^a may be connected together, as indicated in Fig. 3. This circuit-band may be placed upon the wires by any trainman without the necessity of his leaving the train. This is because the wires 6 7^a are located comparatively higher relatively to the track, as indicated in Fig. 2. The wires are mounted by means of posts 21, provided with brackets 22 and supporting insulators 23 24 25, these parts being of the ordinary or any approved 70 construction. Where the wires pass through a tunnel 26, the bracket 22 may be mounted upon the wall of the tunnel, as shown in Fig. 2. The surface rails are shown at 27 and the third rail at 28 29, being thus divided into 80 sections in the usual manner. The third-rail sections are fed by power-mains 30, passing through the conduit 31 in the usual manner.

It will be noted that a block or section of the railway is a block not only for the purpose of signaling, but also for the purpose of supplying power to the rolling-stock. As my invention has no direct relation to the supply of power, however, I do not show nor describe any means for this purpose further than to 85 locate the rails, which may be of the usual pattern.

My invention is used as follows: The dynamo 1 is normally in motion, and the signal lamps and bells are normally inactive, owing 95 to the circuit being incomplete. In case of an accident—such, for instance as a wreck—a trainman takes the circuit-band 20 by its handle 20^a and reaches up from the platform or from a car-window and places the circuit-band 100

upon the wires 6 7^a, as indicated in Fig. 3. The following circuit is thereby completed: source of electricity 1, terminal 2, wire 4, wire 6, circuit-band 20, wire 7^a, thence through 5 all of the bells 8 and glow-lamps 9 in the block B to the insulated wire 10 and also from the wire 7^a through the bell 12 and the glow-lamp 13 to the wire 11 at the power-house, and through this wire to the terminal 3 of the dynamo. This completion of the circuit rings 10 all of the bells 8 in the block B, the bell 12 at the power-house, and also lights all of the lamps 9 in the block B and the lamp 13 at the power-house. The engineer at the power-house thereupon knows that there is trouble 15 in the block B and of course takes proper action, such as cutting off the power from the block or section B and apprising officials of the road, &c. The passengers thereupon leave the train and walk out of the block, it making no difference whether it be in a tunnel or on a clear piece of track. There is no danger from the third rail, owing to the fact that the engineer has cut off the power from 20 the block. The continuous ringing of all of the bells in the block serves to effectively warn the passengers, no matter upon what part of the train they may be, and the lighting of the glow-lamps 9 facilitates the chances 25 for escape without injury. The result is that in a case of accident all of the passengers are apprised of the trouble and every facility is offered them to escape. If a fire is started by a short circuit, it will of necessity extinguish itself upon the cutting off of the power. 30

Having thus described my invention, I claim as new and desire to secure by Letters Patent—

1. In an electric signal system, the combination of a single feed-wire of one sign, a 40 pair of wires of another sign, alarm mechanisms connected in multiple with said last-mentioned wires, a source of electricity connected with said single feed-wires and with one of said wires of another sign, and means controllable at will for connecting the other of said last-mentioned wires with said single feed-wire, thereby actuating all of said alarms. 45

2. In an electric signal system, the combination of a station and a plurality of distinct 50 blocks, a rail-section disposed within each block for supplying power to rolling-stock therein, signaling mechanism disposed within each block and controllable at will, a plurality of separate alarm mechanisms at the station, 55 the signaling mechanisms of the several blocks being separately connected with said alarms,

and mechanism controllable at will, for energizing said signaling mechanism in any desired block independently of other blocks, so that the block affected may be identified from 60 said station.

3. In an electric signal system used in connection with a plurality of separate blocks and a station, the combination of rail-sections each of the length of a block, for supplying 65 power to rolling-stock within said block, a separate group of alarms disposed within each block and distributed substantially throughout the length thereof, separate alarms at the station for each of said blocks, and means controllable at will, for simultaneously energizing the alarms of a predetermined block and the alarm representing said block at the station. 70

4. In an electric signal system used in connection with a plurality of distinct blocks and a station, the combination of a feed-wire in each block, a pair of wires disposed in each block and connected together, means controllable at will, for connecting together in 80 any given block said single feed-wire and one of said pair of wires, a source of electricity connected with said single feed-wire and with the other of said pair of wires, and alarm mechanism disposed at said station and connected with said single feed-wire and with one of said pair of wires. 85

5. In an electric signal system, the combination of alarm mechanism disposed within a block, alarm mechanism disposed at a station, wires for energizing said alarms, said wires being uncovered, and a metallic circuit-band having substantially the form of a metallic hook, provided with a handle of insulating material and entirely disconnected from 90 the wiring, for the purpose of being placed upon and removed from said wires at will. 95

6. In an electric signal system, the combination of alarm mechanism disposed at a station, alarm mechanism disposed within a distant block, open-circuit wiring connecting said alarms together, and a portable hook of conducting material for engaging said wiring and thereby completing the circuit through said alarms. 100

In testimony whereof I have signed my name to this specification in the presence of two subscribing witnesses.

OTTO ERNST.
